(57) **CLAIM**

The ornamental design for a heat sink with a three-dimensional curved surface, as shown and described herein.

DESCRIPTION

FIG. 1 is a perspective view of a heat sink with a three-dimensional curved surface showing our new design;
FIG. 2 is a right side view thereof;
FIG. 3 is a top view thereof;
FIG. 4 is a front view thereof;
FIG. 5 is a bottom view thereof;
FIG. 6 is a left side view thereof; and,
FIG. 7 is a rear view thereof.
